(57) **CLAIM**

The ornamental design for a dispenser head, as shown and described.

DESCRIPTION

FIG. 1 is a top view of one embodiment of our design for a dispenser head with the nozzle in the extended position; FIG. 2 is a top view thereof, with the nozzle in the folded position;

FIG. 3 is top, front and side perspective view thereof, with the nozzle in the extended position;

FIG. 4 is a top, front and side perspective view thereof, with the nozzle in the folded position;

FIG. 5 is a front view thereof, with the nozzle in the extended position;

FIG. 6 is a front view thereof, with the nozzle in the folded position;

FIG. 7 is a top view of another embodiment of our design for a dispenser head with the nozzle in the extended position;

FIG. 8 is a top view thereof, with the nozzle in the folded position;

FIG. 9 is top, front and side perspective view thereof, with the nozzle in the extended position;

FIG. 10 is a top, front and side perspective view thereof, with the nozzle in the folded position;

FIG. 11 is a front view thereof, with the nozzle in the extended position; and,

FIG. 12 is a front view thereof, with the nozzle in the folded position.

The areas shown in broken lines show environmental structure and form no part of the claimed design.
